UNITED STATES PATENT OFFICE

FRIEDRICH SCHWARZ, OF HAMBURG, GERMANY

INTERNAL-COMBUSTION ENGINE

Application filed January 2, 1929, Serial No. 329,820, and in Great Britain November 21, 1928.

The present invention relates to an internal combustion engine with a stepped piston. According to the invention the engine is intended to be used at high speeds and hence 5 the piston must be relieved of lateral pressures due to the connecting rod. For this purpose the stepped-piston is guided during its entire stroke either externally, by means of slippers, or internally, in that it slides 10 over an inner cylinder projecting from the crank case into the piston and sealed therefrom.

The invention is shown by way of example in the accompanying drawings in two 15 structural forms.

Fig. 1 is a vertical sectional view of the engine.

Figs. 2 and 3 are similar views showing modified forms.

20 Fig. 4 is an elevation of the stepped-piston.

The connecting rod *d* is pivotally mounted in the piston *f* at *a*, and is articulated in known manner to the crank, *b*, *c*.

In Fig. 1 a guide is provided in that a gliding member *o* in which the gudgeon pin *a* is received and which projects from the bottom of the piston into the inner cylinder *l*₁ and is guided therein, is made of such a length that it remains during the whole 25 stroke within the inner cylinder *l*₁. *g* is the step piston, which together with the cylinder *l*₁ forms the lower combustion chamber.

The inner surface of the cylinder *l*₁ serves as a gliding path for the guide piece *o*.

30 According to Figs. 2 and 3 the piston *f* is guided by means of its upper part in the cylinder *e*, whereas its lower part glides in an enlarged part of the cylinder *h*, wherein the step piston *g* works. The sealing is effected by means of rings *k* which are let into the cylinder *h*. The step *g* is at the same time formed with slippers *m* and takes up the travelling pressure originating from the connecting rod *d*. By means of the step-piston 35 *g*, the piston *f* and the external cylinder *h*, the annular combustion chamber on one side, and by reason of the piston cover and the cylinder *e* the combustion chamber on the other side is formed.

40 The cylinder *h* may according to Fig. 3,

be prolonged into the crank-case so as to form a cylinder *l* so that the piston is sufficiently guided even at its lower dead point, it being possible to locate the packing rings *k* on the piston.

It is now intended to illustrate the working of the machine according to Fig. 1. In the position shown the stepped piston *f*, *g* has completed the compression stroke and the expansion stroke is about to begin. The ignition of the working medium in the cylinder *e* is effected for instance, by means of spark plugs. The stepped piston *f*, *g* slides by reason of the explosion into its second position. During this stroke the inlet and exhaust valves *p* and *q* are closed because the explosion takes place in the cylinder *e*, but in the cylinder *h* compression takes place. At the end of the period of the explosion that creates the useful work in the cylinder *e* and also of the compression period in the cylinder *h*, the valve *p* is opened, whereas the valve *q* remains closed. As the piston returns to its starting or initial position the exhaust period takes place in the cylinder *e* and the explosion period in the cylinder *h*. Thereafter a second stroke cycle takes place which produces the suction stroke in the cylinder *e*, but the exhaust in the cylinder *h*. For this purpose the two valves *p* and *q* have been opened at the change of the stroke. When the stroke again reverses, which again causes the piston to rise, the compression is effected in the cylinder *e* and the suction in the cylinder *h*, the valve *p* being closed, and the valve *q* opened. In this manner the operation continues as a four stroke cycle.

If it is intended to apply the device to two stroke cycle engines, the operations in the cylinders must be so adjusted, that each stroke is a working stroke. The exhaust, suction and compression periods (scavenging and charging periods) then take place 45 during the explosion stroke in the cylinder *e*, and during the explosion stroke occurring during the return stroke of the piston in the cylinder *h*. In this case the cylinders are provided with scavenging and charging 50

ports, which are covered and uncovered by the stepped piston.

Having now particularly described and ascertained the nature of my said invention and in what manner the same is to be performed, I declare that what I claim is:—

1. An internal combustion engine including a stepped piston and a main cylinder for cooperation with the main portion of the stepped piston, an outer cylinder for cooperation with the stepped portion of the piston, and a guide arranged in axial alignment with the main cylinder and of less external diameter than that of the main cylinder, the upper end of the guide extending within the main cylinder and providing with such main cylinder a guide for the main portion of the piston in all movements thereof, a projection rigid with the main portion of the piston and slidably cooperating with the interior of said guide in all positions of the main piston, and a connecting rod secured to and depending from said projection.
2. An internal combustion engine including a stepped piston, a main cylinder for cooperation with the main portion of the stepped piston, an outer cylinder for cooperation with the stepped portion of the piston, a guide arranged in axial alignment with the main cylinder, a projection rigid with the main portion of the stepped piston and slidably cooperating with the interior of the guide in all operative movements of the stepped piston.
3. An internal combustion engine including an integral piston presenting a main piston and an outer stepped piston, a main cylinder in which the main piston operates, an outer cylinder in which the stepped piston operates, a guide arranged inwardly of the outer cylinder and in axial alignment with both the main and outer cylinders, a projection rigid with the main piston and extending below the plane of the main and stepped pistons, said projection cooperating with the interior of the guide and serving through such cooperation as a continuous guiding element for both the main piston and stepped piston throughout the full operative movement of each.

In testimony whereof I affix my signature.

FRIEDRICH SCHWARZ.
